UNITED STATES PATENT OFFICE

149,449

DESIGN FOR AN ELECTRIC LIGHTING FIXTURE

Martin W. Schwartz and Max J. Marks,
Chicago, Ill.

Application July 1, 1946, Serial No. 131,248

Term of patent 14 years

(Cl. D48—4)

To all whom it may concern:

Be it known that we, Martin W. Schwartz and Max J. Marks, citizens of the United States and residents of Chicago, in the county of Cook and State of Illinois, have invented a new, original, and ornamental Design for an Electric Lighting Fixture, of which the following is a specification, reference being had to the accompanying drawing, forming a part thereof.

In the drawing, Figure 1 is a perspective view of an electric lighting fixture showing our new design as taken from one side thereof intermediate the ends; and Figure 2 is a side elevation of one end of the fixture, both ends being similar.

We claim:

The ornamental design for an electric lighting fixture, as shown.

MARTIN W. SCHWARTZ.
MAX J. MARKS.
